(57) **CLAIM**

The ornamental design for a bottle, as shown and described.

DESCRIPTION

FIG. 1 is a top, front, right perspective view of a bottle;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Any broken lines shown in the drawings are for illustrative purposes only and form no part of the claimed design. Certain features currently not in broken lines may be placed into broken lines in other embodiments while other features in broken lines may be placed into solid lines in other embodiments.
